ELECTROSTATIC PRECIPITATOR

Edward H. R. Pegg, Wilkinsburg, Pa., assignor
to Westinghouse Electric & Manufacturing
Company, East Pittsburgh, Pa., a corporation
of Pennsylvania

Application March 26, 1938, Serial No. 198,247

6 Claims. (Cl. 183—7)

My invention relates to electrical precipitators for atmospheric dust, and particularly, although not necessarily, such precipitators as may be used for the conditioning of air which is to be breathed.

5 The present invention is an improvement over that which constitutes the subject matter of Gaylord W. Penney's application Serial No. 45,070, filed October 15, 1935, Patent No. 2,129,783, granted September 13, 1938, relating to a gas-purifying precipitator in which the gas is blown first through an ionizing chamber, and then through a separate precipitating chamber, a significant feature of the precipitator being that the ionizing wire is of such small diameter that 10 practically utilizable ionization of suspended particles in the gas may be obtained at a wire-charging voltage which is below the critical corona voltage, so that the wire-charging voltage may be below this critical value, thereby limiting the 15 ionizing current input and also limiting the ozone-generation when the precipitator is used for cleaning air.

Such a precipitator utilizes an ionizing wire of less than 32 mils thickness, which is a somewhat rough critical value of the wire-diameter, somewhere near the knee of the curve expressing the relation between the critical corona voltage and the wire diameter. In ordinary practice, the wire is much finer than this upper limit, and is 20 frequently a tungsten wire 5 mils in diameter, or even very much less in diameter. In order to ensure against breakage and to facilitate handling of the equipment, the end-supports for such a fine wire must be fairly rigid and strong, and if the 25 wire is longer than about a foot, it should be supported at frequent intervals along its length, say at every 8 inches, in order to protect it against vibration and breakage, or, in remote cases, against excessive sagging. These supports introduce dark spots along the wire, extending from 30 some half inch to three quarters of an inch on either side of the support, defining regions at which the ionizing current is quite inadequate, so that the air or gas which passes these regions is 35 not adequately ionized, thus reducing the efficiency of the precipitation. It is an object of my invention to avoid the foregoing difficulties.

One object of my invention is to provide suitable means such as baffles or air-guides for ensuring 40 a negligibly small, or greatly reduced, rate of gas-flow past the regions near the supporting-points where there is inadequate ionization.

Another object of my invention is to provide an improved form of intermediate wire-steadying means in the form of a flexible filamentary mem-

ber in tension, lying substantially parallel to the line of gas-flow, and pulling upon the fine ionizing wire with enough force to prevent destructive vibration of the ionizing wire. Such a flexible filamentary member will be so small in physical dimensions that it will not produce the dark space of poor ionization which is characteristic of the more massive rigid intermediate supports which have heretofore frequently been necessary.

With the foregoing objects in view, and others which will become apparent as the description proceeds, my invention consists in the systems, methods, apparatus and combinations hereinafter described and claimed, and illustrated in the accompanying drawing, wherein:

Figure 1 is a longitudinal vertical sectional view of an exemplary form of embodiment of my invention, the section plane being indicated at I—I in Fig. 2;

Fig. 2 is a vertical cross-sectional view, on the plane indicated by the line II—II in Fig. 1, and

Fig. 3 is a top plan view, with parts broken away for clarity of illustration.

In the illustrated embodiment of my invention, 25 which is only one of many forms which the invention can take, air to be treated is drawn in through the top of the precipitator-cabinet 1 through a protective screening 2, and passes downwardly through an ionizing chamber 3 in 30 the top of the cabinet, after which the air continues downwardly and passes through a precipitating chamber 4, the bottom of which discharges into a blower 5 for drawing the air through the apparatus. The outlet of the blower 35 may either discharge the treated air near the floor or the treated air may be led away from the blower by any means and in any manner which may commend itself as desirable.

The ionizing chamber usually comprises a 40 plurality of ionizing units disposed transversely with respect to the direction of air-flow, each ionizing unit consisting of a centrally disposed fine wire 6 which is disposed in spaced relation between two relatively large electrodes 7 which 45 are preferably tubular or curved in section, so that they present curved surfaces toward the ionizing wire, as explained in the aforesaid Penney application. The tubular electrodes 7 are grounded on the precipitator-cabinet 1. The 50 ionizing wires 6 are suspended between rigid metal end-supports 8 carried by a skeleton framework 9 which is supported by insulators 11.

The end-supports 8 must be adequately spaced from the end walls 13 of the cabinet in order 55

to provide adequate insulation. It will thus be seen that the air in the spaces between the end-supports 8 and the end-walls 13 is not adequately ionized, and that this region of inadequate ionization also extends for some half inch to three quarters of an inch in from the end-supports 8. According to one phase of my invention, I provide suitable baffles or other air-directing means for keeping the air-stream from passing over these 10 regions of poor ionization. In the particular embodiment of my invention shown in the drawing, these baffles take the form of end-shields 15 disposed at the ends of the screening 2 at the top of the cabinet 1, so that the air enters the top 15 of the cabinet at points sufficiently removed from the end-walls 13 to prevent, or substantially prevent, the air-stream from playing over the points where the end-supports 8 engage the wires 6.

Unless the wires 6 are very short, it will usually 20 be found desirable to steady these wires at one or more intermediate points between the end-supports 8. In accordance with my invention, I have preferred to accomplish this process through the utilization of one or more flexible filamentary means 16, in tension, which may consist of phosphor-bronze or tungsten wire, of say, 10 mils diameter, not necessarily quite as small as the ionizing wire 6, but small enough so that it does not seriously hinder the flow of ionizing current 25 at the point where the steadyng wire 16 hooks over the ionizing wire 6. The steadyng wire or filamentary member 16 is supported by a rigid stub 17 connected to the skeleton framework 9 and extending a short distance toward the ionizing wire 6, so that the hooked wire 16 lies substantially parallel to the gas-flow. By being in tension, the hooked wire-support 16 pulls the ionizing wire 6 just slightly out of a straight line, so that the ionizing wire is prevented from vibrations which would quickly cause its breakage.

40 The precipitating chamber 4 consists of a large number of spaced insulated plates 20 and grounded plates 21, spaced closely together, and disposed parallel to the direction of air-flow. The insulated precipitating plates 20 are supported by 45 notched metallic supports 22 which are carried by insulators 23. The non-insulated precipitating plates 21 are supported and spaced by means of notched plates 24 carried by the cabinet 1.

50 As explained in the aforesaid Penney application, the ionizing wires 6 and the insulated precipitator-plates 20 are unidirectionally charged with respect to the uninsulated or grounded parts. Because of the greater spacing between each wire 55 6 and its associated tubular electrodes 7, as compared with the spacing between the alternate plates 20 and 21 of the precipitator chamber, the ionizing voltage is frequently higher than the precipitating voltage. I have indicated that unidirectional voltages are applied to the ionizing wires 6 and the precipitator-plates 20 by showing leads 50 and 26, respectively, marked on the drawing as being energized, respectively, by the positive terminal of the unidirectional ionizing source of voltage I_+ , and by the positive terminal of the unidirectional precipitating source of voltage P_+ , the negative terminals (—) being grounded on the frame of the cabinet 1, as indicated at 30.

70 In operation, the air entering the top of the cabinet 1, as shown by the arrows, is first ionized in the ionizing chamber 3, so as to charge the particles which are suspended in the incoming air. The air then passes through the precipitating chamber 4 where the charged suspended particles 75 become attracted to the oppositely charged pre-

cipitating plates, after which the purified air is withdrawn from the cabinet by the blower 5. When the precipitator, particularly the precipitating plates, become dirty by reason of the foreign particles extracted from the air, in the course of weeks or months, the precipitator may be taken outdoors and washed with a hose, after which it is again ready for use.

By my invention, it will be observed that the efficiency of precipitation is increased by the 10 measures which I have taken to combat the difficulties heretofore experienced as the result of dark regions along the ionizing wires 6, where inadequate ionization is obtained. When I refer to the dark regions around the supporting-points 15 of the ionizing wire, as obtained in previous structures utilizing massive wire-supports 8 without means for providing supplementary ionization at these points, I refer to regions which appear to be dark when viewed in a dark room. Normally, 20 there will be a slight discharge or corona-glow which is distinctly visible in a dark room, in the immediate vicinity of the ionizing wires 6, when the precipitator is operating correctly, but this phenomenon is distinctly different from the 25 corona-discharge which is visible in sunlight and which requires a much higher ionizing voltage than I utilize on my wires 6. I term the lowest voltage which produces a corona-discharge of the sort which is visible in sunlight the critical corona 30 voltage of the wire. My present invention follows the practices explained in the aforesaid Penney application, in utilizing an ionizing voltage which is considerably lower than this critical corona voltage, this practice being made possible by the 35 utilization of a sufficiently fine ionizing wire. When I refer to dark spaces appearing around the ionizing wire, therefore, I refer to spaces which seem dark in a darkened room, and not to spaces which seem dark in the sunlight.

40 While I have described my invention in a preferred form of embodiment, and have suggested certain limits in accordance with my best understanding of the same at the present time, I desire it to be distinctly understood that I am not 45 altogether limited to these limits or understandings, or to the particular form of embodiment shown in the drawing. I desire, therefore, that the appended claims shall be accorded the broadest construction consistent with their language 50 and the prior art.

I claim as my invention:

1. A gas-purifying precipitator comprising an ionizing chamber, a separate precipitating chamber, and means for causing a gas-flow successively through first said ionizing chamber and then said precipitating chamber; said ionizing chamber being provided with one or more ionizing units, each unit being disposed transverse to the gas-flow and comprising oppositely charged electrodes comprising a single fine wire spaced between relatively large electrodes, and an intermediate steadyng-means for said fine wire, said intermediate steadyng-means comprising a flexible filamentary member in tension, for pulling said fine wire only slightly out of a straight line, said steadyng-means lying substantially parallel to the direction of gas-flow; said precipitating chamber comprising oppositely charged, spaced precipitating electrodes substantially parallel to the direction of gas-flow; and means associated with both the ionizing chamber and the precipitating chamber for unidirectionally charging said oppositely charged electrodes; said fine wire or wires being of less than 32 mils diameter and be- 75

ing of such fineness that substantially utilizable ionization of suspended particles in the gas is obtained at a wire-charging voltage below the critical corona voltage, and the wire-charging voltage being below said critical corona voltage.

2. A gas-purifying precipitator comprising an ionizing chamber, a separate precipitating chamber, and means for causing a gas-flow successively through first said ionizing chamber and then said precipitating chamber; said ionizing chamber being provided with one or more ionizing units, each unit being disposed transverse to the gas-flow and comprising oppositely charged electrodes comprising a single fine wire spaced between relatively large electrodes, one or more relatively rigid supporting-means for said fine wire, and gas-directing means disposed in sufficiently close relation to the supporting-points of the fine wire for ensuring a greatly reduced rate of gas-flow past one or more of said supporting-points of said fine wire; said precipitating chamber comprising oppositely charged, spaced precipitating electrodes substantially parallel to the direction of gas-flow; and means associated with both the ionizing chamber and the precipitating chamber for unidirectionally charging said oppositely charged electrodes comprising a single fine wire spaced between relatively large electrodes, one or more relatively rigid supporting-means for said fine wire, and gas-directing means disposed in sufficiently close relation to the supporting-points of the fine wire for ensuring a greatly reduced rate of gas-flow past one or more of said supporting-points of said fine wire; said precipitating chamber comprising oppositely charged, spaced precipitating electrodes substantially parallel to the direction of gas-flow; and means associated with both the ionizing chamber and the precipitating chamber for unidirectionally charging said oppositely charged electrodes.

3. A gas-purifying precipitator comprising an ionizing chamber, a separate precipitating chamber, and means for causing a gas-flow successively through first said ionizing chamber and then said precipitating chamber; said ionizing chamber being provided with one or more ionizing units, each unit being disposed transverse to the gas-flow and comprising oppositely charged electrodes comprising a single fine wire spaced between relatively large electrodes, and an intermediate steadyng-means for said wire, said intermediate steadyng-means comprising a flexible filamentary member in tension, for pulling said wire only slightly out of a straight line, said steadyng-

means lying substantially parallel to the direction of gas-flow; said precipitating chamber comprising oppositely charged, spaced precipitating electrodes substantially parallel to the direction of gas-flow; and means associated with both the ionizing chamber and the precipitating chamber for unidirectionally charging said oppositely charged electrodes.

4. A gas-purifying precipitator comprising an ionizing chamber, a separate precipitating chamber, and means for causing a gas-flow successively through first said ionizing chamber and then said precipitating chamber; said ionizing chamber being provided with one or more ionizing units, each unit being disposed transverse to the gas-flow and comprising oppositely charged electrodes comprising a single fine wire spaced between relatively large electrodes, one or more relatively rigid supporting-means for said fine wire, and gas-directing means disposed in sufficiently close relation to the supporting-points of the fine wire for ensuring a greatly reduced rate of gas-flow past one or more of said supporting-points of said fine wire; said precipitating chamber comprising oppositely charged, spaced precipitating electrodes substantially parallel to the direction of gas-flow; and means associated with both the ionizing chamber and the precipitating chamber for unidirectionally charging said oppositely charged electrodes.

5. The invention as defined in claim 1, characterized by the relatively large electrodes of the ionizing chamber having a limited effective extent in the direction lengthwise of said filamentary steadyng-means so that said relatively large electrodes are, for the most part, more closely spaced from the fine wire than from said filamentary steadyng means.

6. The invention as defined in claim 3, characterized by the relatively large electrodes of the ionizing chamber having a limited effective extent in the direction lengthwise of said filamentary steadyng-means so that said relatively large electrodes are, for the most part, more closely spaced from the fine wire than from said filamentary steadyng means.

EDWARD H. R. PEGG.
